UNITED STATES PATENT OFFICE

FRANK KUHN AND LAWRENCE H. THOMAS, OF DETROIT, MICHIGAN, ASSIGNORS TO AMERICAN ELECTRICAL HEATER COMPANY, OF DETROIT, MICHIGAN, A CORPORATION OF MICHIGAN.

ELECTRICALLY-HEATED INSTRUMENT.

1,356,071.

Specification of Letters Patent. Patented Oct. 19, 1920.

Application filed June 11, 1920. Serial No. 388,230.

To all whom it may concern:

Be it known that we, FRANK KUHN and LAWRENCE H. THOMAS, each a citizen of the United States of America, residing at Detroit, in the county of Wayne and State of Michigan, have invented certain new and useful Improvements in Electrically-Heated Instruments, of which the following is a specification, reference being had therein to the accompanying drawings.

The invention relates to electrically heated instruments, being more particularly designed for use in connection with electrically heated sad irons, and the invention consists in the novel construction of means for housing the terminal block as herein-after set forth.

In the drawings:

Figure 1 is a longitudinal section through a portion of a sad-iron to which my improvement is applied;

Fig. 2 is a perspective view of the removable cover;

Fig. 3 is a similar view of the attachment; and

Fig. 4 is a plan view.

In the manufacture of electrically heated sad irons, as well as other electrically heated instruments, it is usual to carry the terminal contacts out from the casing through an insulator block. This block is apertured for the passage of the terminals therethrough and is mounted upon the portions of said terminals which extend upward from the heating unit, but externally the block must fit an aperture in the housing which surrounds the unit. It is difficult to obtain such exactness in the construction of the heating unit that the terminal block will exactly register with the aperture in the housing so that more or less clearance must be provided for the block in said aperture. Furthermore, where the terminals extend out from the housing at an oblique angle, this necessitates forming a boss or projection upon the housing to surround the block, which renders the finishing of the housing more difficult. With my improvement perfect registration is obtained by forming the portion of the housing which surrounds the block separate from the housing which encloses the unit, and this also facilitates the finishing of the housings. Furthermore, by making the block housing of a stamping the

unit housing may be formed from cast metal without necessity of either cushioning the aperture for the block or the forming of the same to closely fit the block.

As specifically shown, A is the base of a sad iron, B is the electrical heating unit therefor, which is clamped in position by the pressure plate C and clamping screws D. These screws have threaded portions for engaging the nuts E that clamp the pressure plate and upward extensions which pass through the housing or cover plate F, which incloses the unit. They are also used for securing the handle G to said housing by means of the nuts H. I are the terminals extending upward from the unit within the housing F and J is the insulator block apertured for the passage of said terminals.

Instead of forming the housing F to fit above the block J, an aperture K is formed therein of sufficient size to receive the block with the clearance, thereby providing for any inaccuracies in registration. L is a sheet metal stamping, which forms a housing for the projecting portion of the block and which is provided with a rearwardly extending shank M apertured for the passage of the stud or clamping screw D. This shank is preferably embossed to form a spacer between the housing F and the handle G and the aperture in the shank is sufficiently enlarged so as to permit adjustment of the member L with respect to the block J.

With the construction described, the housing F prevents a flat upper face, which may be readily finished as there are no obstructing projections. The housing L may also be separately finished. In assembling, after the housing F is placed upon the base A, the shank M of the housing L is sleeved upon the screw D and said member is engaged with the block J. The handle is then placed upon the stud and the whole clamped by the nut H. This will bind the parts together, so that the housing L will retain the block J and prevent displacement thereof.

To guide the connector socket into engagement with the terminal posts, a guide ring N is preferably mounted upon the handle G, but this feature forms no part of the invention.

What we claim as our invention is:

1. The combination with an electrical

- heating unit, terminals projecting therefrom and an insulator block mounted on said terminals, of a housing for inclosing said unit apertured for the passage of said block, and a separate housing or casing for the block secured to said first-mentioned housing and having a limited adjustment relative thereto.
2. The combination with an electrical heating unit, terminals projecting therefrom, an insulator block mounted on said terminals and a housing apertured for the passage of said block therethrough, and a separate housing or casing fitting about the portion of said block projecting through said first-mentioned housing, said separate housing being adjustable with respect to said first mentioned housing, and means for clamping the two housings in fixed relation to each other.
3. The combination with an electrical heating unit, terminals therefor projecting obliquely therefrom and an insulator block mounted on said terminals, of a housing apertured for the passage of said terminals and insulator block therethrough and providing clearance to compensate for inaccuracies in registration, and a separate casing or housing complementary to said first-mentioned housing and engaging the portion of said insulator block projecting beyond said first-mentioned housing, and means for clamping said housings directly and in fixed relation to each other.
4. The combination with a sad iron, of an electrical heating unit therefor, terminals projecting from said unit and a terminal block mounted on said terminals, a housing for inclosing said unit, a clamping stud for said unit projecting upward and through said housing, a handle for said housing, and a housing for a portion of said insulator block projecting through said first-mentioned housing, said last-mentioned housing having an apertured shank engaging said clamping stud between said handle and first-mentioned housing.
5. The combination with an electrical heating unit, of a housing therefor, terminals projecting outward through an aperture in said housing, an insulator block mounted on said terminals and loosely fitting said aperture and projecting beyond said housing, and an auxiliary housing closely fitting said insulator block and covering said aperture.
6. In an electrically heated sad iron, the combination of a base, a heating unit, a clamping plate for said heating unit, a housing or cover plate for inclosing said heating unit and clamping plate, terminals for said unit projecting outward through an aperture in said housing, an insulator block mounted on said terminals arranged in said aperture and projecting beyond said housing, a handle, a clamping screw for attaching said handle and housing to said base, and an auxiliary housing for inclosing the projecting portion of said insulator block and covering said aperture, being provided with a shank secured between said handle and housing by said clamping screw.
7. In an electrically heated sad iron, the combination with a base, of a heating unit mounted thereon, a housing or cover plate for inclosing said unit, terminals for said unit projecting outward through an aperture in said housing, a terminal block mounted on said terminals located in said aperture and projecting beyond said housing, a handle, a clamping screw for securing said handle and housing to said base, and an auxiliary housing for fitting said insulator block and covering said aperture, an auxiliary housing consisting of a sheet metal stamping provided with a shank apertured for the passage of said clamping screw and secured between said handle and housing.
8. In an electrically heated instrument, the combination with a heating unit, of a housing for inclosing the same having a flat top, terminals for said housing projecting outward through an aperture in said flat top, an insulator block mounted on said terminals located within said aperture and projecting beyond said housing, and an auxiliary housing formed of a sheet metal stamping for fitting said insulator block, inclosing the projecting portion thereof and covering said aperture, and means for clamping said auxiliary housing to said first-mentioned housing, permitting a limited adjustment relative thereto.

In testimony whereof we affix our signatures.

FRANK KUHN.
LAWRENCE H. THOMAS.
